UNITED STATES PATENT OFFICE.

CHARLES RICHTER, OF CAMDEN, NEW JERSEY.

ELECTRIC-RAILWAY SYSTEM.

SPECIFICATION forming part of Letters Patent No. 419,709, dated January 21, 1890.

Application filed May 4, 1889. Serial No. 309,609. (No model.)

To all whom it may concern:

Be it known that I, CHARLES RICHTER, of Camden, in the county of Camden and State of New Jersey, a citizen of the United States, 5 have invented certain new and useful Improvements in Electric-Railway Systems, of which the following is a specification.

This invention relates to an improved electric-railway system which is run without the use of overhead wires by arranging the conductors in a tunnel between the rails; and the invention consists of an electric railway in which the conducting-wire is arranged in sections along the road and connected at the 10 end of each section by switches with stationary resistances located at uniform distances from each other. One pole of the electromotor on the car is connected by a trolley or contact-roller with the conducting-wire, while 15 the other pole of the motor is connected by a conducting-cable with a small contact-wagon which travels in a tunnel at a distance somewhat greater than the length of one section from the car. The conducting-cable can be 20 wound up more or less and the speed of the motor regulated by switching out one or more of the resistances along the line and increasing thereby the current that is supplied to 25 the motor.

30 In the drawings, Figure 1 represents in diagram form my improved system; and Fig. 2 is an enlarged view showing a portion of the conduit with the conductor located therein, the resistances and the switches between the 35 sections, with the switch-operating devices, being also shown in this figure. The connection between the trolley-carriage and the car is modified in this figure from that shown in Fig. 1. Fig. 3 is a transverse section through 40 the conduit, showing the conductor, the trolley carried by the car, the switches between the sections, and the resistances.

For carrying my improved system into practical operation the conducting line-wire 45 L of the railway is divided into a number of sections of nearly-uniform length. At the ends of the sections are arranged, preferably in man-holes between and below the track, a number of resistances R, which are connected 50 by the conducting-wire L with the current-generating dynamo D at the station A, from which the railway is operated. The current

is supplied to the electromotors on the cars in series by one wire on a double-track road, the wire running along one track and returning along the other. In case of a single track, the return-wire is insulated and carried back either underground or overhead, as desired. The resistances R are in circuit with the conducting-wire, and the sections of the conductor are connected by means of switches S, automatically opened by a suitable switch-opening device O on the car, the switches being normally in closed position, so as to cut out the resistances. A contact trolley or 60 brush r is arranged below each car C on the arm b, projecting into the conduit from the car and connected with an electromotor M. The contact-roller r is connected with one pole of the motor M, while the other pole of 65 the motor is connected by a conducting-cable C' with a small traveling truck or contact-wagon H at some distance from the car. The cable C is passed over a roller or winding-drum a on the car and can be wound up on 70 the same by the attendant, the roller being provided with a suitable indicator, so as to indicate the distance of the contact-wagon from the car. The contact-wagon H travels in the tunnel, if one is used. The distance 75 between the track and the car should cover one section of the conducting-wire at a time for a certain speed; but if a greater speed is required the cable connecting the car with the contact-wagon may be elongated, so that 80 the distance of the same from the car is slightly greater than two lengths of sections of the conducting-wire, by which means two resistances are brought into action and the current supplied to the motor is doubled. A 85 greater speed can also be obtained by increasing the resistances between the sections along the road. As the car passes over the switch, the same is opened by the switch-opener O on the car, while a switch-closing device h 90 of the contact-wagon will close the switch again. The switches consist simply of a hub having insulated faces and contact-faces, and this hub is provided with pins extending at the end into the path of the switch-operating 95 parts O h. By opening the switch S a path of less resistance is opened through the contact-roller on the contact-wagon and over the cable to the motor, and from the motor over 100

the contact-roller on the car to the conducting-wire, as this path offers less resistance than that of the resistance R , and the greater part of the current is thereby forced to pass through the motor, so that the car is propelled thereby. The current passes then over the return-wire back to the second pole of the dynamo at the station. The dynamo is operated in the usual manner by an engine E at the station. The remaining parts of the current which passes through the stationary resistance, and is to some extent wasted, can be utilized by arranging storage-batteries B at certain points along the road, taking the place of resistances, which storage-batteries may be used for incandescent lighting or power purposes. As the car passes from one section of the conducting line-wire to the other it opens the switches one after another between the sections where the resistances are located, and thus compels the current to seek the path of least resistance over the contact-wagon, cable, and electromotor and contact-roller on the car back to the conducting-wire, so as to keep up in this manner the motion of all the cars along the track. The contact-wagon, which travels in the rear of each car, closes the switch again and cuts out the resistance, so as to place it into proper position for the next car, and so on.

Having thus described my invention, I claim as new and desire to secure by Letters Patent—

1. An electric-railway system composed of a conducting-wire divided into sections, a stationary resistance at the end of each section, a switch between the sections, a car having a contact-roller, an electromotor on said car, a contact-wagon at some distance from the car, a conducting-cable connecting the electromotor with the contact-wagon, and devices respectively on the car and contact-wagon truck for opening and closing the switches, substantially as set forth. 35

2. The combination, in an electric-railway system, of a conducting-wire divided into sections, a stationary resistance interposed at the end of each section, switches between the sections, a car having a contact-roller, an electromotor on said car, a contact-wagon at 50 a distance greater than the length of one section of the conducting-wire, a conducting-cable for connecting the motor and contact-wagon secured to a winding drum or roller at one end, and devices on the car and contact-wagon for opening and closing the switches as the car and truck pass, respectively, over the same, substantially as set forth. 55

In testimony that I claim the foregoing as my invention I have signed my name in presence of two subscribing witnesses.

CHARLES RICHTER.
